UNITED STATES PATENT OFFICE.

ROBERT L. GIBSON, OF PHILADELPHIA, PENNSYLVANIA.

SOUND-BOX FOR TALKING-MACHINES.

990,973.

Specification of Letters Patent.

Patented May 2, 1911.

Application filed November 28, 1905. Serial No. 289,410.

To all whom it may concern:

Be it known that I, ROBERT L. GIBSON, of the city and county of Philadelphia, State of Pennsylvania, have invented an Improvement in Sound-Boxes for Talking-Machines, of which the following is a specification.

My invention relates particularly to the means for supporting the stylus bar, and its object is to increase the sensitiveness and 10 volume of the sounds transmitted without decreasing their timbre and sharpness.

In another application, Serial No. 284,646, filed October 27th, 1905, I have described a stylus bar support consisting of a spring 15 structure arranged at right angles to the plane of the diaphragm of the sound box, and the present invention relates to a supporting device of this general character.

More particularly the present invention 20 relates to the employment in a supporting device of this kind of a leaf or flat spring supported at its ends transversely to the plane of the diaphragm and connected with the stylus bar between its ends, so that, 25 while great sensitiveness to direct vibration in the plane of the diaphragm is preserved, the resistance to lateral or torsional movement is increased. Not only is the construction beneficial in increasing the amplitudes 30 and accuracy of the sound transmitted, but it is simple, economical and easily applied.

In the drawings: Figure 1 is an elevation of a talking machine embodying the invention; Fig. 2 is a front elevation of the sound 35 box; Fig. 3 is an elevation of the upper edge of the sound box; and Fig. 4 is a transverse sectional view on the line X—X of Fig. 2 enlarged.

A is the rotating record carrying disk or 40 table; B is the horn; C is the swinging sound conveying arm; and D is the sound box suspended from the arm, with which it may be connected in any suitable manner.

While the particular construction of the 45 sound box,—aside from the stylus bar support—is not material to my invention, I have, for purposes of illustration, shown a sound box of the general character shown in the Jones Patent No. 628,813, dated July 50 11th, 1899, in which the diaphragm F is clamped between flexible rings F' F' within the head E of the sound box, and the tubular sleeve of the head G is clamped between rings H H of non-sound-conducting 55 material. The stylus bar J is secured at one end to the center of the diaphragm F

in the usual manner and is provided at the other end with a clamp K of any convenient construction, for holding the stylus or needle point. 60

The support for the stylus bar consists of a flat spring L, arranged transversely to the plane of the diaphragm and supported by the head. It is connected with the stylus bar between its ends. In the construction 65 shown, M is a frame carried by the head of the sound box and having notches m m into which the ends of the spring L are sprung, thereby curving the spring and putting it under tension. The bar J extends through 70 the spring and frame M and may be secured to the former in any suitable manner, as by solder. With a spring support of this kind extending transversely to the plane of the diaphragm, and hence to the plane of 75 vibration of the point of connection between the stylus bar and diaphragm the stylus bar is made very sensitive to the direct vibration, while lateral or torsional vibration is practically eliminated and this resistance to 80 lateral or torsional movement is greatly increased by the use of the flat spring. This support, therefore, by reason of its sensitiveness to direct vibration and of its resistance to lateral or torsional movement transmits the sound waves with great amplitude 85 and accuracy, and not only increases the volume but preserves the timbre and tone.

While it is not new to connect the bar to a spring supported at its ends and arranged 90 transversely to the plane of the diaphragm, in former constructions of this kind the spring is not the sole means of supporting and sustaining the stylus bar, but is the means of holding the stylus bar on a fulcrum between a portion of the stylus bar and the head upon which the bar vibrates. In my construction the spring acts not as a means of holding the bar upon a stationary fulcrum but as the sole means of supporting 95 the bar and the usual stationary fulcrum is dispensed with. The bar vibrates at the point of connection with the spring and on a stationary or fixed fulcrum.

What I claim as new and desire to secure by Letters Patent, is as follows:

1. In a sound-box for talking machines, the combination of a head or case and diaphragm, a substantially rectangular flat spring supported at its opposite ends only, 110 said sole points of support and the spring being in a line transverse to the plane of the

- diaphragm, and a stylus bar connected with the spring between the ends thereof, said spring having the function of a fulcrum and yieldingly supporting and holding said bar 5 in its normal position.
2. In a sound-box for talking machines, the combination of a head or case and diaphragm, a substantially rectangular flat spring bent transversely to its length so as 10 to be under tension and supported at its opposite ends only, said sole points of support and the spring being in a line transverse to the plane of the diaphragm, and a stylus bar connected with the spring between and in 15 line with the ends thereof, said spring having the function of a fulcrum and yieldingly supporting and holding said bar in its normal position.
3. In a sound-box for talking machines, 20 the combination of a head or case and diaphragm, a supporting frame carried by the case having two oppositely directed shoulders, a substantially rectangular flat spring supported at its opposite ends only by the 25 shoulders of said frame, said sole points of support of the frame and the spring being in a line transverse to the plane of the diaphragm, and a stylus bar connected with the spring between the ends thereof, said 30 spring having the function of a fulcrum and yieldingly supporting said bar in its normal position.
4. In a sound box for talking machines,
- the combination of the head or case and diaphragm, of a transverse supporting frame M carried by the head and arranged transversely to the plane of the diaphragm, the flat spring L having its ends sprung into engagement with said support and extending transversely to the plane of the diaphragm and a stylus bar acting on the diaphragm and connected with said spring. 35
5. In a sound-box, a case having two supports arranged parallel to and at different distances from the diaphragm, a diaphragm 40 located to one side of a plane through said supports, a flat spring sprung between the supports so as to be under tension and in a plane at right angles to the plane of the diaphragm, and a stylus secured to the spring 45 intermediate of its ends and supported wholly by the spring and out of direct contact with the case. 50
6. In a sound box, the combination with a stylus, of a spring support therefor, and a spring supporting plate, the ends of said spring support being secured to the plate, and the central portion of said spring support being sprung away from the said plate. 55
- In testimony of which invention, I hereunto set my hand. 60
